UNITED STATES PATENT OFFICE

THOMAS B. HOLBERT, OF WORTHINGTON, WEST VIRGINIA

BALLOT BOX

Application filed July 28, 1930. Serial No. 471,112.

This invention relates to ballot boxes, and it has for its primary object to provide a simple and practical form of ballot box which shall possess various advantages over the 5 common forms of ballot boxes now in use.

A further object is to provide, in association with a main ballot box, a second, or auxiliary, ballot box of a smaller size than said main box and adapted to be nested 10 within the latter for convenient transportation from headquarters to the place of voting, it being designed that the boxes shall be employed interchangeably at the voting place, one for receiving the votes as cast while 15 the counting board is counting votes from the other.

With these and other important objects in view, the invention resides in the features of construction, arrangement of parts and 20 combinations of elements which will herein-after be fully described, reference being had to the accompanying drawings, in which—

Figure 1 is a perspective view of the invention;

25 Figure 2 is a top plan view of the invention, showing in elevated position the flap employed for closing the ballot-entering slot;

Figure 3 is an under side elevation of said cover;

30 Figure 4 is a section on line 4—4, Fig. 2, showing the nested arrangement of boxes; and—

Figure 5 is an enlarged detail section on line 5—5, Fig. 4.

35 Referring to said drawings, 1 designates the front wall and 2 the rear wall of the body of a ballot box of rectangular form. Suitably hinged to the upper portion of the

40 rear wall 2 is the rear edge portion of a lid or cover 3 which constitutes a closure for said body, and rigidly mounted upon the front edge portion of said cover is the member 4 of a hinge-like device which has as its other member a hasp 5. Said hasp is designed

45 to be disposed vertically against the front wall of the box, having therein a slot 6 for the reception of a staple for having a padlock 7 or other securing means attached thereto, said staple being rigidly mounted on said front wall.

Provided in the cover 3 at a suitable point, preferably adjacent to the rear edge, is a longitudinally extending slot 8 through which folded ballots to be deposited within the box are introduced. Disposed on the 55 under side of the cover and slideable into and out of closing relation to said ballot-entering slot 8 is a plate 9, the opposite lateral edges of said plate being received and movable within ways 10 afforded beneath the relatively facing flanges of parallel transversely disposed L-shaped guides 11 which are rigidly mounted upon the under side of said cover. A depending lug 12 fixed on the 60 under side of the cover in an appropriate position constitutes a stop against which a flexible tongue 13 carried by the front edge portion of the slide-plate 9 may seat, or abut, when said plate occupies its retracted position wherein it closes the ballot-entering slot 8, said lug 12 and said tongue being so interengageable for preventing return shifting of said slide-plate from its slot-closing position except when the cover 3 is raised, permitting 65 access to the tongue for lifting the latter out of abutting relation to said lug.

An upstanding lug or pin 14 fixed on the top face of the slide-plate 9 projects upward through a transversely extending slot 15 in the cover and provides means whereby shifting by hand of said plate may be effected for retracting the latter and also for advancing said plate following disengagement of the tongue relative to the stop 12. The tongue is sufficiently flexible that, in advance movement of the slide-plate, it will ride over said stop following hand elevation thereof relative to said stop.

70 Said slide-plate is designed primarily as a temporary closure for the ballot-entering slot 8, as during the time that the box is being transported from the voting room to the vote-counting room.

75 As a precaution against tampering with the slide-plate 9 following shifting of the latter to the position in which it closes the ballot-entering slot 8, and also to provide a more permanent closure for said slot, as when ballots are being transported to and from headquarters, a cover-plate or flap 16 is provided,

the same having hinged connection with the cover 3 at a point rearward with respect to said slot 8 and being adapted to be secured in closely overlying relation to said slot and the pin 14. In the closed position of said flap, a staple 17 carried on the under side of its front end projects through an aperture 18 provided therefor in the cover 3 and is adapted to be secured against withdrawal from said aperture, as by a readily applicable and removable wire clip 19 of loop form.

A second ballot box 20, which may have a construction identical with that hereinbefore described, may be provided, the same being of such smaller dimensions that for convenience in transporting from and to headquarters, it may be nested within the first described box, as shown in Fig. 4, there being sufficient clearance between the covers of the boxes when so nested to provide space for ballots. A suitable carrying handle 21 of loop form is borne by the cover 3 of the larger box. A flexible strap 22 adapted to be disposed in closely embracing relation to the larger box is provided, the same including a buckle 23 by means of which its ends are attached. Following closing of the ballot box, said strap is adjusted in place, being passed between the handle 21 and the cover 3 to prevent slipping thereof outward over an end of the box. A seal 24 of paper or other suitable material, which may bear the names of election officials, is applied by means of a suitable adhesive substance to the strap, one end portion of such seal being affixed to the free projecting end of the strap and the other end portion thereof being affixed to an adjacent body portion of said strap, as shown in Fig. 1. Obviously, said seal must be broken to permit access to the box and thus constitutes means whereby tampering with the box may readily be detected.

What is claimed is—

1. A ballot box comprising a box body, a hinged cover for said body, means for securing said cover in closing relation to said body, said cover having therein a ballot-entering slot, means carried on the under side of said cover shiftable to and from closing relation to said slot, a pin carried by said shiftable means and projecting outwardly through the cover whereby movement of said shiftable means may be effected, a flap hinged on said cover and adapted to be moved to and from overlying covering relation both to said slot and to said pin, and means engageable with said flap and accessible only when said cover is raised whereby said flap is secured in such covering relation.

2. A ballot box comprising a rectangular box body, a hinged cover for said body, means for securing said cover in closing relation to said body, said cover having therein a ballot-entering slot means on the under side of said cover shiftable into and out of closing relation to said slot, a flap hinged on the outer side of said cover and adapted for movement to and from overlying closing relation to said slot, and means accessible only when said cover is raised whereby both said flap and said shiftable means are secured in closing relation to said slot.

3. A ballot box comprising a rectangular box body, a hinged cover for said body, means for securing said cover in closing relation to said body, said cover having therein a ballot-entering slot, a flap hinged on said cover and adapted for movement to and from overlying closing relation to said slot, said flap having a member which, in the slot-closing position thereof, projects inwardly through said cover, and means engageable with said member for securing said flap in its said closing position, the last mentioned means being accessible only when said cover is raised.

4. A ballot box comprising a rectangular box body, a hinged cover for said body, means for securing said cover in closing relation to said body, said cover having therein a ballot-entering slot, a flap hinged on said cover and adapted for movement to and from overlying closing relation to said slot, said flap having a member which, in the slot-closing position thereof, projects inwardly through said cover, means engageable with said member for securing said flap in its said closing position, the last mentioned means being accessible only when said cover is raised.

5. A ballot box comprising a rectangular box body, a hinged cover for said body, means for securing said cover in closing relation to said body, said cover having therein a ballot-entering slot, a flap hinged on said cover and adapted for movement to and from overlying closing relation to said slot, said flap having a member which, in the slot-closing position thereof, projects inwardly through said cover, means engageable with said member for securing said flap in its said closing position, the last mentioned means being accessible only when said cover is raised, a strap adapted to be secured in encircling relation to said box and said cover following closing of the latter, and a breakable seal applied in connecting relation to opposite end portions of said strap.

6. A ballot box comprising a rectangular box body, a hinged cover for said body, means for securing said cover in closing relation to said body, said cover having therein a ballot-entering slot, a flap hinged on said cover and adapted for movement to and from overlying closing relation to said slot, means accessible only from within the box whereby said flap is secured in closing relation to said slot, and temporary closing means for said slot consisting of a plate shiftable mounted on the under side of said cover and having a pin-like member projecting upwardly through the latter and adapted to be grasped for imparting to said plate shifting movements.

In testimony whereof I affix my signature.
THOMAS B. HOLBERT.
